PROCESS FOR HYDROGEN TREATMENT AND CATALYTIC CRACKING OF PETROLEUM HYDROCARBONS

Harold Beaufier and Richard A. Flinn, Penn Hills Township, Allegheny County, Pa., assignors to Gulf Research & Development Company, Pittsburgh, Pa., a corporation of Delaware

Filed Apr. 14, 1958, Ser. No. 728,102

7 Claims. (Cl. 208—89)

This invention relates to the preparation of lower boiling materials from a crude petroleum which contains sulfur and metalliferous impurities.

Crude petroleums containing relatively large amounts of vanadium and sulfur constitute a difficult problem in regard to conversion of the higher boiling fractions into lower boiling materials by catalytic cracking. The sulfur and vanadium impurities have a harmful effect on the cracking catalyst. Also such crudes frequently yield residue having a high carbon residue so that they cannot be catalytically cracked without deposition of large amounts of coke on the cracking catalyst. A method frequently used to process such crudes is to distill off the lower boiling fractions including gas oil and then subject the undistilled residue to a coking operation. This coking operation is not attractive since it produces large amounts of low value coke.

This invention has for its object to provide an improved procedure for the conversion of crude petroleum which contains metal and sulfur compounds into lower boiling hydrocarbons such as gasoline by procedure which includes catalytic cracking. Another object is to provide economical procedure for the conversion of petroleum which contains vanadium compounds and sulfur into lower boiling hydrocarbons of higher value without forming large amounts of by-products of low value. Another object is to improve the state of the art. Other objects will appear hereinafter.

These and other objects of our invention are accomplished by subjecting a crude petroleum which contains sulfur and vanadium to distillation to distill off lower boiling fractions of the petroleum and to leave a residue having a weight percent sulfur to weight percent vanadium which equals at least 200—the sulfur and vanadium being determined on the basis of the amount of these elements present and not the amount of compounds of these elements. This undistilled residue is subjected to treatment with hydrogen in the presence of a sulf-active hydrogenation catalyst at a pressure between about 1750 and 4500 p.s.i.g., at a temperature from about 750° to 815° F., with a liquid hourly space velocity from about 0.25 to 10, the product from the hydrogenation is subjected to distillation to remove materials boiling below gas oil which are formed during the hydrogen treatment. The residue from the second distillation constituting the gas oil and heavier components is then subjected to catalytic cracking.

We have found in accordance with our invention that economical conversion into a catalytic cracking stock can be obtained by subjecting only the higher boiling compo-

2

nents of these low grade crudes to the hydrogenation treatment. However, we have also discovered that if the first mentioned distillation, to obtain the reduced crude, is carried too far, the sulfur-vanadium ratio is made too low and the hydrogenation treatment will not effectively reduce the vanadium impurities to an extent sufficient to produce a suitable catalytic cracking charge stock from the residue. In other words the initial distillation should not be carried to an extent sufficient to result in an undistilled residue having a sulfur to vanadium ratio below about 200. Otherwise it will not be possible during the hydrogenation treatment to reduce the vanadium content to a sufficiently low value that it will not harmfully affect the cracking catalyst. Thus the vanadium content of the product after hydrogenation should be about one part per million or less if subsequent deactivation of the cracking catalyst is to be avoided. This value cannot be obtained unless the first distillation is carried out only to an extent sufficient to give a reduced crude charge stock having a sulfur-vanadium ratio above about 200.

In the following examples and description we have set forth several of the preferred embodiments of our invention, but it is to be understood that they are given by way of illustration only and not in limitation thereof.

Vanadium is known to have a harmful effect on catalytic cracking catalysts. In order to avoid this harmful action the charge stock to the catalytic cracking operation should contain less than about one part per million of vanadium. The procedure of our invention is applicable to any crude petroleum or residual fraction thereof which contains vanadium in amounts sufficient to rapidly and adversely affect the activity of a cracking catalyst such as a vanadium content between about 2 and 1500 parts per million. The charge stock to our procedure must contain sulfur impurities in amounts between about 0.20 and 10.0 percent by weight. Of course the sulfur to vanadium ratio in the charge to the initial distillation must be above 200. Crudes which contain vanadium impurities in large amounts also usually contain sulfur impurities in large amounts. The invention therefore is applicable to any crude petroleum or residual fraction thereof such as reduced or topped crude which contains sulfur and vanadium in the amounts mentioned.

The initial distillation has as its primary objective the removal of lower boiling components of the crude petroleum such as gasoline, fuel oil, etc. These straight run fractions of lower boiling point usually contain relatively small amounts of impurities, particularly metalliferous impurities, and can be utilized most economically without subjecting them to the hydrogenation treatment. The objective in the first distillation is also to obtain a bottoms fraction of smaller volume which can be more economically treated in the more expensive hydrogenation operation. While it is necessary from an economic standpoint to utilize a smaller bottoms fraction in the hydrogenation treatment, nevertheless it is essential that the distillation should not be carried to a point such that the sulfur to vanadium ratio is below about 200. Otherwise the hydrogenation treatment will not effectively reduce the vanadium content. During the distillation the sulfur impurities distill at a higher rate than the vanadium, and it is a simple matter to analyze the undistilled residue to determine when the sulfur to vanadium ratio approaches the minimum value of 200. We pre-

fer to distill until a sulfur to vanadium ratio of between about 270 and 420 is obtained. The degree of distillation in the first distillation must be a balancing of two factors. On the one hand the low boiling fractions should be removed so that they can be utilized as such or processed by less expensive procedures than hydrogenation (i.e. direct scale or catalytic cracking of light oil and reforming of the gasoline). On the other hand the distillation should not be extensive enough to lower the sulfur-metal ratio below about 200. It would of course be advantageous, if removal of vanadium was the only matter to be considered, to utilize as high a sulfur to vanadium ratio as possible. However, as pointed out above, this would means that the whole crude would be subjected to the hydrogenation treatment, and this is not ordinarily economically feasible. The amount of lower boiling materials removed from the initial charge stock by the first distillation will depend upon the nature of the particular crude, such as the sulfur and vanadium impurity content and the amount of lower boiling components present. Therefore it is not possible to specify any degree of distillation in order to obtain the desired reduction in volume and minimum sulfur to metal ratio. However, as pointed out above, the degree of distillation required can be readily determined by analysis of the undistilled residue during the distillation or by a small scale analytical distillation to determine the amount of distillation required.

The undistilled residue from the first distillation is then subjected to the hydrogenation treatment. This hydrogen treatment is carried out by contacting the residue from the distillation with hydrogen under the conditions specified above while in the presence of a catalyst which retains its activity in the presence of sulfur compounds, i.e. a sulf-active catalyst. Examples of suitable catalysts are the oxides and sulfides of group VI metals such as molybdenum, tungsten, vanadium, etc. used alone or in combination with oxides or sulfides of iron group metals such as nickel, cobalt or iron. The catalysts may be fluidized, i.e. suspended in the hydrocarbon vapors and hydrogen or may be in the form of a fixed bed. The catalysts may be composited with a carrier such as activated alumina, alumina-silica, "Alfrax," kieselguhr, etc. The reaction conditions are preferably 2000 to 3200 p.s.i.g., 775° to 800° F. and a liquid hourly space velocity of 0.5 to 2. Hydrogen is recycled at a rate of between about 1000 and 20,000 and preferably between about 2000 and 12,000 s.c.f./bbl. By utilizing these reaction conditions, the sulfur and vanadium are efficiently removed from the residual hydrocarbon charge stock with minimum concomitant conversion of the hydrocarbon into lower boiling materials and coke. Therefore by operating at these conditions, the heavy residual charge stock undergoes purification to a high quality catalytic cracking charge stock with relatively little conversion into lower boiling materials or formation of coke. Since there is little coke formed, the on-stream period for the hydrogenation is unusually long, i.e. about 150 to 4000 hours. Therefore relatively infrequent regeneration of the hydrogenation catalyst is required. After the catalyst has lost activity due to coke deposition, it can be regenerated in known manner by combustion with air or other oxygen-containing gas at a temperature between about 800° and 1400° F.

After the above described hydrogenation operation, the product from the hydrogenation is subjected to a second distillation to remove the relatively small amount of lower boiling materials formed during the hydrogenation treatment. It is desirable to remove all of the material boiling below gas oil in this distillation. Thus gasoline and lower boiling fuel oils are preferably removed in this second distillation. The undistilled residue from this second distillation is then subjected to catalytic cracking. The invention has the unusual advantage that the

initial procedures described above result in such an efficient removal of vanadium and sulfur that the undistilled residue from the hydrogenation treatment can be directly contacted with a catalytic cracking catalyst without adverse effect on the catalyst. Nickel impurities also occur in crude petroleum and are harmful to cracking catalysts. However, if the subject matter of our invention is carried out as described above, i. e. by observing the required sulfur-vanadium ratio, the nickel will be reduced to a low and harmless value along with the vanadium. In other words the hydrogenation treatment will reduce the vanadium content to below about one part per million with analogous reductions in nickel content and these amounts of metal impurities are not harmful to a catalytic cracking catalyst. Also the carbon residue is markedly reduced so that less coke is deposited on the cracking catalyst. The cracking catalyst may be any conventional or known cracking catalyst such as natural or synthetic silica-alumina cracking catalysts, cracking catalysts of high alumina-low silica content, silica-magnesia cracking catalysts, etc. The catalytic cracking operation may utilize either a fixed bed or a fluidized bed, and the catalytic cracking conditions may be any conditions which are conventionally used.

In the accompanying drawing numeral 2 designates a fractionating column into which the charge stock which contains sulfur and metalliferous impurity is introduced via conduit 4. The charge stock is fractionated in column 2 and a light fraction is removed via conduit 6. The undistilled residue having a sulfur to vanadium ratio above about 200 is removed through conduit 8 and is mixed with hydrogen introduced through conduit 10. The mixture of these two components flows through conduit 12 into hydrogen treating zone 14 where the above described action resulting in lowering of the sulfur and metal content takes place. The product from the hydrogen treating zone flows through conduit 16 into still 18 where lighter portions formed during the hydrogen treatment are distilled off through conduit 20. The bottoms fraction from still 18 flows through conduit 22 and is subjected to catalytic cracking in catalytic cracking zone 24. The products of catalytic cracking are then removed through conduit 26.

EXAMPLE

A Middle Eastern, a Mid-Continent and a Venezuelan crude having the inspections shown in Table I were subjected to distillation to obtain reduced crudes. The Middle Eastern and Mid-Continent crudes were subjected to vacuum tower distillation and atmospheric distillation to obtain the reduced crudes and a vacuum reduced crude was prepared from the Venezuelan crude.

The atmospheric and vacuum tower bottoms from these crudes were then treated with hydrogen in the presence of the hydrogenation catalysts listed in Table II composited with an alumina carrier. The hydrogen treatment was carried out under the temperature, pressure, space velocity and hydrogen recycle conditions set forth in Table II. The atmospheric and vacuum tower bottoms fractions treated had the sulfur-vanadium ratios set forth in Table II. The results of the hydrogen treatment on the sulfur, vanadium and nickel contents of the products are shown in Table II.

Table I

¹ MEVTB=Middle Eastern vacuum tower bottoms. MEATB=Middle Eastern atmospheric tower bottoms. MCVTB=Mid-Continent vacuum tower bottoms. MCATB=Mid-Continent atmospheric tower bottoms. RVC=Reduced Venezuelan crude.

From the data presented in Table II, it will be evident that the utilization of a sulfur to vanadium ratio above about 200 resulted in effective removal of both sulfur and vanadium, and specifically yielded products having the desired 1 part per million or less of vanadium which is necessary for catalytic cracking charges.

The furnace oil free residue from the product obtained in Run #6 of Table II was subjected to catalytic cracking. For comparison a Kuwait virgin gas oil was also catalytically cracked under the same conditions (space velocity wt./hr./wt. of 1.5; temperature of 930° F. and "S.R. Filtral" catalyst). The inspections on the charge stocks to the catalytic cracking are given in Table III, and the inspections on the products from catalytic cracking are given in Table IV.

We claim:

1. The process which comprises in combination subjecting a member of the group consisting of crude petroleum and residual fractions thereof which contain vanadium in amounts above 2 and below 1500 parts per million and sulfur in amounts between about 0.20 and 10.0 percent by weight and which has a sulfur-to-vanadium ratio above 200 to a first distillation to remove lower boiling straight run fractions, said distillation being terminated before a sulfur to vanadium ratio below about 200 is reached, subjecting the undistilled residue from the first distillation to contact with hydrogen at a pressure between about 1750 and 4500 p.s.i.g., at a temperature of between about 750° and 815° F., at a liquid hourly space velocity of about 0.25 and 10 at a hydrogen recycle rate of between about 1000 and 20,000 s.c.f./bbl. in the presence of a sulf-active hydrogenation catalyst, subjecting the product from the hydrogenation treatment to a second distillation to remove materials boiling below about gas oil and to obtain an undistilled residue con-

stituting gas oil and higher boiling portions and subjecting the undistilled residue from the second distillation without elimination of any of the components thereof to catalytic cracking to convert the undistilled residue into lower boiling hydrocarbons.

2. The process which comprises in combination subjecting a crude petroleum which contains vanadium in amounts above 2 and below 1500 parts per million and sulfur in amounts between about 0.20 and 10.0 percent by weight and which has a sulfur-to-vanadium ratio above 200 to a first distillation to remove lower boiling straight run fractions, said distillation being terminated before a sulfur to vanadium ratio below about 200 is reached, subjecting the undistilled residue from the first distillation to contact with hydrogen at a pressure between about 2000 and 3200 p.s.i.g., at a temperature of between about 775° and 800° F., at a liquid hourly space velocity between about 0.5 and 2 at a hydrogen recycle rate of between about 2000 and 12,000 s.c.f./bbl. in the presence of a sulf-active hydrogenation catalyst, subjecting the product from the hydrogenation treatment to a second distillation to remove materials boiling below about gas oil and to obtain an undistilled residue constituting gas oil and higher boiling portions and subjecting the undistilled residue from the second distillation without elimination of any of the components thereof to catalytic cracking to convert the undistilled residue into lower boiling hydrocarbons.

3. The process which comprises in combination subjecting a crude petroleum which contains vanadium in amounts above 2 and below 1500 parts per million and sulfur in amounts between about 0.20 and 10.0 percent by weight and which has a sulfur-to-vanadium ratio above 200 to a first distillation to remove lower boiling straight run fractions, said distillation being terminated before a sulfur to vanadium ratio below about 200 is reached, subjecting the undistilled residue from the first distillation to contact with hydrogen at a pressure between about 2000 and 3200 p.s.i.g., at a temperature of between about 775° and 800° F., at a liquid hourly space velocity between about 0.5 and 2, at a hydrogen recycle rate of between about 2000 and 12,000 s.c.f./bbl. in the presence of a catalyst selected from the group consisting of oxides and sulfides of metals of group VI of the periodic system and oxides and sulfides of group VI of the periodic system mixed with a member of the group consisting of oxides and sulfides of metals of the iron group, subjecting the product from the hydrogenation treatment to a second distillation to remove materials boiling below about gas oil and to obtain an undistilled residue constituting gas oil and higher boiling portions, and subjecting the undistilled residue from the second distillation without elimination of any of the components thereof to catalytic cracking to convert the undistilled residue into lower boiling hydrocarbons.

4. The process which comprises in combination subjecting a crude petroleum which contains vanadium in amounts above 2 and below 1500 parts per million and sulfur in amounts between about 0.20 and 10.0 percent by

weight and which has a sulfur-to-vanadium ratio above 200 to a first distillation to remove lower boiling straight run fractions, said distillation being terminated before a sulfur to vanadium ratio below about 200 is reached, subjecting the undistilled residue from the first distillation to contact with hydrogen at a pressure between about 2000 and 3200 p.s.i.g., at a temperature of between about 775° and 800° F., at a liquid hourly space velocity between about 0.5 and 2, at a hydrogen recycle rate of between about 2000 and 12,000 s.c.f./bbl. in the presence of a catalyst selected from the group consisting of oxides and sulfides of metals of group VI of the periodic system and oxides and sulfides of group VI of the periodic system mixed with a member of the group consisting of oxides and sulfides of metals of the iron group, subjecting the product from the hydrogenation treatment to distillation to remove materials boiling below about gas oil and to obtain an undistilled residue constituting gas oil and higher boiling portions, subjecting the undistilled residue from the second distillation without elimination of any of the components thereof to catalytic cracking to convert the undistilled residue into lower boiling hydrocarbons and continuing the above process for a period of time between about 150 and 4000 hours and until sufficient coke has accumulated on the catalyst to require regeneration, regenerating the catalyst by combustion and reusing the regenerated catalyst in the above process.

5. The process which comprises in combination subjecting a crude petroleum which contains vanadium in amounts above 2 and below 1500 parts per million and sulfur in amounts between about 0.20 and 10.0 percent by weight and which has a sulfur-to-vanadium ratio above 200 to a first distillation to remove lower boiling straight run fractions, said distillation being terminated when a sulfur to vanadium impurity ratio of about 270 to 420 is reached, subjecting the undistilled residue from the first distillation to contact with hydrogen at a pressure between about 1750 and 4500 p.s.i.g., at a temperature of between about 750° and 815° F., at a liquid hourly space velocity between about 0.25 and 10, at a hydrogen recycle rate of between about 1000 and 20,000 s.c.f./bbl. in the presence of a cobalt molybdate catalyst, subjecting the product from the hydrogenation treatment to a second distillation to remove materials boiling below about gas oil and to obtain an undistilled residue constituting gas oil and higher boiling portions and subjecting the undistilled residue from the second distillation without elimination of any of the components thereof to catalytic crack-

ing to convert the undistilled residue into lower boiling hydrocarbons.

6. The process which comprises in combination subjecting a crude petroleum to a first distillation at atmospheric pressure to remove lower boiling straight run fractions vaporizable at atmospheric pressure, subjecting the undistilled residue from the first distillation to contact with hydrogen at a pressure between about 2,000 and 3,200 p.s.i.g., at a temperature of between about 775° and 800° F., at a liquid hourly space velocity between about 0.5 and 2 at a hydrogen recycle rate of between about 2,000 and 12,000 s.c.f./bbl. in the presence of a catalyst comprising essentially cobalt molybdate, subjecting the product from the hydrogenation treatment to a second distillation to remove materials boiling below about gas oil and to obtain an undistilled residue constituting gas oil and higher boiling portions and subjecting the entire undistilled residue from the second distillation to catalytic cracking to convert the undistilled residue into lower boiling hydrocarbons.

7. The process which comprises in combination subjecting a crude petroleum to a first distillation at atmospheric pressure to remove lower boiling straight run fractions vaporizable at atmospheric pressure, subjecting the undistilled residue from the first distillation to contact with hydrogen at a pressure between about 2,000 and 3,200 p.s.i.g., at a temperature of between about 775° and 800° F., at a liquid hourly space velocity between about 0.5 and 2 at a hydrogen recycle rate of between about 2,000 and 12,000 s.c.f./bbl. in the presence of a catalyst comprising essentially nickel tungstate, subjecting the product from the hydrogenation treatment to a second distillation to remove materials boiling below about gas oil and to obtain an undistilled residue constituting gas oil and higher boiling portions and subjecting the entire undistilled residue from the second distillation to catalytic cracking to convert the undistilled residue into lower boiling hydrocarbons.
